MINIATURE BOWLING ALLEY TABLE

August Uhr, Cibolo, Tex.

Application June 26, 1939, Serial No. 281,236

2 Claims. (Cl. 273—47)

The invention relates to a game apparatus and more especially to a miniature bowling alley table.

The primary object of the invention is the provision of a table of this character wherein its build has therein several bowling alleys, the pins therefor being automatically set up and the balls for the striking of said pins being adapted to travel over an area so that these balls by chance will operate a scoring device and in this manner players participate in several games, namely, in the playing of a bowling game and a chance game.

Another object of the invention is the provision of a table of this character wherein the bowling pins are controlled for the automatic setting up thereof in a novel manner and the balls for the striking of the pins will be caused to travel over a game area so that these balls will effect a scoring for the participants in the playing of the bowling game, the table in its entirety being of novel construction.

A further object of the invention is the provision of a table of this character wherein through the use of bowling pins and balls several games can be played at one and the same time and in this way lending amusement and entertainment to the players in use of such table.

A further object of the invention is the provision of a table of this character which is simple in its construction, thoroughly reliable and efficient in operation, enabling dual games to be played thereon, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

In the accompanying drawings:

Figure 1 is a fragmentary side elevation of a table constructed in accordance with the invention.

Figure 2 is a fragmentary top plan view thereof.

Figure 3 is a sectional view taken on the line 3—3 of Figure 4 looking in the direction of the arrows.

Figure 4 is a sectional view taken on the line 4—4 of Figure 3 looking in the direction of the arrows.

Figure 5 is a fragmentary vertical longitudinal sectional view showing in detail the chance game area of the table.

Figure 6 is a fragmentary vertical longitudinal sectional view showing in detail by full lines one of the pins in set up position and by dotted lines in a knock down position.

Figure 7 is a detail elevation of the counting device employed with the table.

Figure 8 is a fragmentary vertical longitudinal sectional view through the ball receiving end of the table.

Figure 9 is a detail plan view of the setting disc for the pins employed with the table.

Similar reference characters indicate corresponding parts throughout the several views in the drawings.

Referring to the drawings in detail, A designates generally the table constituting the present invention and comprises a body formed with spaced parallel bowling alleys 10 and 11 respectively, these being identical to each other and are superposed with relation to a ball return 12 located intermediate of and coextensive with the major extent of the said alleys 10 and 11. The body formed as before stated is supported upon legs or uprights 13 while said alleys are provided with open ends 14 and opposite closed ends 15, respectively, the latter being in the form of wells 16 for the trapping of balls 17 when thrown or put in motion from the open ends 14 of said alleys.

These balls are imitative of billiard balls and the same are played by the use of cues, not shown, used for the playing of billiards and such cues are used by the players for the sending of the balls in the alleys 10 and 11 for the playing of the bowling game. The wells 16 have formed therein lateral inwardly inclined shelves 18 so that the balls 17 when reaching the said wells from the alleys 10 and 11 will gravitate upon the shelves 18 and discharge upon an incline 19 leading to the chute 12, whence these balls will travel to a retrieving box 20 located at the open ends of the alleys 10 and 11 but intermediate with respect thereto. The chute 12 is preferably of hopper formation and has built therein a step or dropping area 21 so that one portion of the chute will be at a higher plane than the remaining portion yet the said chute inclines in the direction of the open ends of the alleys 10 and 11.

Next to the wells 16 and a part of the alleys 10 and 11 are pin setting stations 22 for the respective alleys and each station has formed therein openings 23 being grouped in spaced relation to each other for the proper setting of bowling pins 24 in the conventional manner for 55

the playing of a bowling game. Each pin 24 has connected to a base 25 therefor a setting chain 26 connected to a setting disc 27 provided with a central coupling stud 28 connected with a bell crank lever 29 pivoted at 30 for vertical swing in a fixed bearing 31 in the frame of the table A. At the open end of each alley 10 and 11 is an operating lever 32 having pull rod connection 33 with the bell crank lever 29 and when the pins 24 have been knocked down on operating the lever 32 these pins can be set up automatically at the station 22. Each bell crank lever 29 has connected thereto a coiled tensioning spring 34 which is fixed in the frame of the table A and the purpose of each spring is to slacken the chains 26 when the pins 24 have been brought to set up position at the stations 22 and thus will not hinder the knocking down of the pins on the striking of a ball 17 thereon when put in play in the alleys 10 and 11.

The alleys 10 and 11 at the longer opposite sides thereof are provided with the usual gutters 35 leading to the wells 16 and these gutters convey the balls to the latter when they run off of the playing surface of said alleys.

In the step area 21 of the chute 12 is a peg playing field 36 which has delivery openings 37 therein for the dropping of the balls 17 thereon through on to a treadle 38 hinged at 39 and spring tensioned at 40. This treadle has operating connection 41 with a scoring or indicator device 42 bracketed at 43. The pegs 44 are distributed on the field 36 so as to make it difficult for a ball 17 traveling over this field to have entrance through a hole 37 for the operation of the treadle 38. If the ball fails to drop through a hole 37 it gravitates over the field 36 and through the chute 12 to the retrieving box 20. A ball 17 when making a hole 37 and by its dropping upon the treadle 38, the device 42 is actuated for exhibiting a scoring point or indicia as at 45 in favor of the participant playing the said ball which is primarily used in an alley 10 or 11 for bowling purposes in knocking down a pin or pins 24 set up at a station 22 within such alley.

The device 42 includes a ratchet feeder 46 cooperating with ratchet teeth 47 on a rotating dial 48 carrying the indicia 45, the latter being visible through a sight opening 49 built in said device 42.

The pegs 44 in the playing field 36 are so positioned to effect hazards for the prevention of a ball 17 in its travel going directly to the holes 37 in said field 36 and in this way making it difficult for the ball to drop through such holes when traveling through the chute 12 in finding

its way to the retrieving box 20. This box 20 is built with a hinge door 50 enabling the balls contained therein to be removed therefrom yet resisting the accidental rolling of the balls from the said box.

The playing field 26 which is actually the step in the area 21 has a descending lip 51 which directs the balls from the elevated portion of the chute to the lowermost portion thereof after the ball has traversed the field 26 and missed a hole 37 in this field.

The bowling game is played similarly to a regular game of bowling while the scoring device 42 is effective for the playing of a chance game and the one acquiring the highest number 15 is the winner of the participants therein, or the users of the table.

What is claimed is:

1. An apparatus of the kind described comprising a supporting frame, an elongated ball rolling alley built in said frame and having opposite open and closed ends, a well at the closed end of said alley, gutters parallel with and at opposite sides of the alley for opening into the well, a laterally and longitudinally inclined shelf within said well, an inclined ball return chute below the plane of the alley and at one side thereof and having communication with the said well, the shelf at two edges only at right angles to each other being removed with respect to walls adjacent thereto of the well for effecting openings at right angles to each other between the well and the said chute, and a retrieving box communicating with the chute and located next to the open end of said alley.

2. An apparatus of the kind described comprising a supporting frame, an elongated ball rolling alley built in said frame and having opposite open and closed ends, a well at the closed end of said alley, gutters parallel with and at opposite sides of the alley for opening into the well, a laterally and longitudinally inclined shelf within said well, an inclined ball return chute below the plane of the alley and at one side thereof and having communication with the said well, the shelf at two edges only at right angles to each other being removed with respect to walls adjacent thereto of the well for effecting openings at right angles to each other between the well and the said chute, a retrieving box communicating with the chute and located next to the open end of said alley, and a door at the outermost side of said box, free for inward opening movement and latched against outward opening movement.

AUGUST UHR.
